(57) **CLAIM**

We claim the ornamental design for snap-on handle for a container, as shown and described.

DESCRIPTION

FIG. 1 is a perspective view showing our new design.

FIG. 2 is a front elevational view thereof.

FIG. 3 is a right side elevational view thereof; the left side elevational view being a mirror image thereof.

FIG. 4 is a top plan view thereof; and,

FIG. 5 is a bottom plan view thereof.
